BAND-PASS FILTER FOR CHANGE OF WAVE

Rudolf Weber, Berlin, Germany, assignor to Telefunken Gesellschaft für Drahtlose Telegraphie m. b. H., Berlin, Germany, a corporation of Germany

Application March 25, 1937, Serial No. 132,901
In Germany March 12, 1936

3 Claims. (Cl. 178—44)

The practical demand arises occasionally to make the band width of receivers changeable inside wide limits say, between 1 and 15 k. c. This demand will be made, for instance, if in airplane receiver apparatus a change is made from beam direction finding to the so-called impulse type of direction finding. In this latter instance, the impulses, in rectangular shape, must be faithfully reproduced in the Braun tube so that a wide band must be received.

When a change to such a wide band is made, detuning of the oscillation circuits is inevitable. Hence, the condition of untuning would have to be corrected by the addition of condensers or coils. However, switches carrying radio frequency energy are undesirable because of additional damping and the requisite shielding.

Now, the invention discloses a circuit arrangement in which these drawbacks are avoided by reason that the switches carry no radio frequency energy or practically so. In one switch position, two paralleled series arrangements of condensers, all of like capacity, serve as a coupler capacity being common to the oscillation circuits, whereas in the other switch position one of these condensers, to avoid detuning, is separately connected in each of the two oscillation circuits and another suitable coupling is chosen.

The invention shall be explained in more detail in what follows and with reference to the accompanying drawing wherein:

Fig. 1 shows the circuit organization of the invention.

Fig. 2 shows the circuit connections obtained when the switches are in the positions illustrated in Fig. 1 whereby transmission of a wide frequency band is effected, and Fig. 3 shows the circuit connections obtained when the switches are in the positions opposite to those illustrated in Fig. 1 whereby the transmission of a narrow frequency band is effected.

Referring to Fig. 1, there are shown a pair of coupled tuned circuits C_x-L . In one of the switching positions, only the switch S_1 is closed so that the four similar condensers C_1-C_4 jointly act like a single condenser C_x of the size of the individual condensers as shown in Fig. 2. The coupling in this connection is very close, for which reason, to minimize crevassing or the production of a double peaked resonance curve, damping resistances W_1 and W_2 are included in the circuit. The coupling insured by condenser C , Fig. 1, is only very loose contrasted with the coupling due to C_x .

In the other switch position, switches S_2 and

S_3 are closed, while switch S_1 is opened. The circuit in this condition is shown in Fig. 3. Condensers C_3 and C_4 as well as the resistances W_1 and W_2 are thus rendered inoperative, while condensers C_1 and C_2 no longer operate as coupling condensers, but are merely included in the oscillation circuits and avoid detuning, for in the switch position shown in Fig. 3, each oscillation circuit C_x-L contains an additional condenser, namely, the coupling condenser C_1 and C_2 , respectively. In the circuit illustrated in Fig. 3 the coupling between the oscillation circuits is effected only by condenser C and it is so loose that the ensuing band width is limited. But in lieu of this coupling also any other coupling could be employed.

What I claim is:

1. A band-pass filter network comprising a pair of similar, tunable circuits, each including an inductance, a variable condenser, a resistance and a pair of fixed condensers all connected in series in the order named, a series coupling condenser connected between high potential ends of said inductances, a conductive connection between the low potential ends of said inductances, switch mechanism individually associated with each tunable circuit for short circuiting the resistance and one of the fixed condensers when in closed position, and other switch mechanism conjointly associated with both tunable circuits and connected between the respective junctions of the short circuited resistance and fixed condenser, whereby the frequency band to be transmitted may be selectively varied within wide limits without altering the tuning of the circuit, upon opening the first switch mechanism and closing the second switch mechanism, and vice versa.

2. A band-pass filter network comprising a pair of similar oscillation circuits, each comprising a variable condenser, an inductance, a resistance and two equal capacities, all connected in a closed circuit, a coupling condenser connected between the high potential ends of the two inductances, a conductive connection between the low potential ends of said inductances, a switch connected between low potential ends of the two circuits, between the common terminals of the resistance and one of the two equal capacities in each circuit, and a switch in each circuit shunting said resistance and said one of the two equal capacities, the arrangement being such that upon operation of the first switch to closed position and with the two last mentioned switches in open position the circuits are adjusted to pass a wide band of frequencies, while

the closing of the two last mentioned switches and the opening of the first switch adjusts the circuits to pass a narrow band of frequencies, in each case the oscillation circuits being tuned to substantially the same resonant frequency.

3. A band-pass filter network comprising a pair of tunable circuits, each including an inductance and a variable condenser, a series coupling condenser connected between the high potential ends of said inductances, a conductive connection between the low potential ends of said inductances, a plurality of fixed condensers common to said pair of tunable circuits and serving as a parallel coupling capacity, said series

coupling condenser and said parallel coupling capacity being of such magnitudes that the circuits are closely coupled to pass a wide frequency band, and means for converting said network to one capable of passing a narrow frequency band comprising a first switching mechanism for causing the plurality of fixed condensers to become ineffective as a parallel coupling capacity and a second switching mechanism individual to each tunable circuit for short circuiting certain of the fixed condensers and switching into said tunable circuits others of said fixed condensers.

RUDOLF WEBER.
